UNITED STATES PATENT OFFICE.

HUBERT I. KEIM, OF STEELTON, PENNSYLVANIA.

BRICK.

1,281,976.

Specification of Letters Patent.

Patented Oct. 15, 1918.

Application filed April 10, 1914. Serial No. 330,964.

To all whom it may concern:

Be it known that I, HUBERT ISAAC KEIM, a citizen of the United States, residing at Steelton, in the county of Dauphin and State of Pennsylvania, have invented certain new and useful Improvements in Bricks; and I do hereby declare the following to be a full, clear, and exact description of the invention, such as will enable others skilled in the art 10 to which it appertains to make and use the same.

This invention relates to building bricks and the primary object of the invention is the provision of a building brick to be used 15 in the construction of arcuate arches or other arcuate portions of a building which is constructed so as to be held against accidental dislodgment by the interlocking relation of one brick with another, which object is carried out by the peculiar forming of the 20 sides, edges and faces of the building brick, some being disposed obliquely with respect to the others as is clearly shown in the drawings.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts 35 throughout the several views, and in which:—

Figure 1 is a fragmentary view of a building showing a number of the improved arched bricks positioned for forming an 10 arcuate arch.

Fig. 2 is a sectional view on the line 2—2 of Fig. 1.

Fig. 3 is a plan view of one of the improved arch bricks.

Fig. 4 is a side view of the brick.

Fig. 5 is a side elevation of the brick showing the side opposite to the one illustrated in Fig. 4.

Fig. 6 is an end view of the brick.

Fig. 7 is a view showing the opposite end of the brick to that illustrated in Fig. 6.

Fig. 8 is a detail perspective view of the brick.

Referring more particularly to the draw-

ings, 1 designates the body of a building 35 brick, which may be constructed of any suitable material, such as is commonly employed in the construction of building bricks and it is of greater width at one end thereof than the other as is clearly shown in Figs. 1 and 3 of the drawings, so as to provide for the forming of an arcuate arch of greater diameter at its outer or upper edge than at its inner or lower edge, as is clearly shown in Fig. 1 of the drawings. The brick body 1 65 has its diagonally opposite longitudinally extending corners cut away as is clearly shown in Fig. 6 of the drawings. The flanges 2 and 3 which are left by the cutting away of the corners of the brick body 70 have their inner faces cut obliquely to the faces of the brick body 1 and oppositely to each other, leaving the opposite ends of the flanges 2 and 3 of increased thickness with respect to the remaining opposite ends of 75 the flanges as is clearly shown in Fig. 7 of the drawings, so that when the bricks are positioned for engagement with each other for forming an arcuate building arch, the respective flanges will fit within the cut away 80 corners of the brick next thereto, preventing the accidental dislodgment of one brick with respect to the other, when the entire arch has been properly formed and keyed or pushed to its permanent position. 85

If it is desired, the ends 4 and 5 of the brick body 1 may be cut arcuate or perfectly straight, as is necessary for the proper construction and appearance of the arch in the construction of which the bricks are employed, this feature being left to the discretion of the person manufacturing the same or being regulated by conditions.

In reducing the invention to practice certain minor features of construction may necessitate alterations to which the patentee is entitled provided such alterations are comprehended within the scope of what is claimed.

What is claimed is:—

As a new article of manufacture, a brick 100 comprising a solid body portion having its side edges gradually tapered from the upper portion thereof toward its lower portion, and plane side walls, opposite alternating 105 flanges formed on the longitudinal ends of said body, said flanges extending the entire height of the body, the inner faces of said

flanges being cut obliquely to the faces of the body and opposite to each other, so that the opposite ends of said flanges are increased in thickness with relation to their remaining opposite ends, whereby said brick can be securely wedged against adjacent bricks to form an arcuate arch.

In testimony whereof I affix my signature in presence of two witnesses.

HUBERT L. KEIM.
